MICROMETER STRING TENSION DEVICE
FOR VIOLINS AND THE LIKE

Ernest W. Hoyt, Kalispell, Mont.

Application June 8, 1934, Serial No. 729,705

3 Claims. (Cl. 84—312)

The object of the invention is to provide an attachment for mounting on the neck of a musical instrument of the violin family to provide for a fine adjustment of the strings following the usual adjustment made with the pegs, so that the pitch of the strings may be determined with a nicety; to provide a device of this character which is applicable to the instrument without any other attachment thereto than its connection with the strings; and generally to provide an attachment of this character which is of simple form, susceptible of cheap manufacture and of a construction that will make for its attachment without any particular skill on the part of the user.

With this object in view, the invention consists in a construction and combination of parts of which a preferred embodiment is illustrated in the accompanying drawing, wherein:

Figure 1 is a longitudinal sectional view of the free end of the neck of a violin in the region of the peg box, showing the invention applied in operative position.

Figure 2 is a top plan view of the structure of Figure 1.

Figure 3 is a sectional view on the plane indicated by the line 3—3 of Figure 1.

Designed for the nice adjustment of the strings 10, after the general rough adjustment made with the pegs 11, the device serves as a micrometer adjustment to raise or lower the pitch of the strings, as desired. For example, the best results come by setting the "A" string at standard pitch, the "D" and "G" strings slightly sharp of the "dead" fifth, and "E" string slightly flat of the "dead" fifth. Such an adjustment is highly difficult if not impossible when using the pegs alone. To this end the invention provides for the mounting of a frog 12 on the neck 10 above the peg box 14. This frog is made preferably of celluloid, or any other suitable material than metal and is stepped as indicated at 15 to provide seats for the milled nuts 16, the latter threadingly engaging the shanks of screws 17 which pass through body openings in the stepped portions of the frog and, adjacent their lower ends, are formed with slots 18, opening on their peripheries, so that the slotted ends may be in the form of hooks which engage the strings 10 between the bridge 19 and the pegs 11.

The nuts 16 bearing upon the frog 12 retain it in position on the instrument neck by reason of the pull exerted on the screws by the strings 10 and after adjustment of the strings with the pegs, the fine adjustment, or tempered tuning of the instrument, is effected by adjusting the nut 16 for the screw of each string, to raise or lower the pitch of the latter, as desired.

The use of the device provides for easily and effectively maintaining the tuning of the instrument without the frequent use of the tuning pegs, thus providing for a longer wear of the instrument strings as well as easy tuning by students and children, etc., after the rough tuning by the performer.

The invention having been described, what is claimed as new and useful is:

1. In combination with a stringed musical instrument having a peg box, a frog spanning the peg box on the open side and seated on the upper edges thereof, a string tensioning member extending through the frog and adjustably mounted therein, the said member engaging a string to apply tension thereto and at the same time retain the frog in position on the box.

2. In combination with a stringed musical instrument having a peg box, a frog seated on the peg box, screws extending through the frog and engaging the strings to apply a tension thereto adjacent the pegs, and a micrometer adjustment on said screws, the frog being stepped and the screws extending through the frog in said steps, and nuts threadingly engaged with the screws and bearing upon the steps of the frog.

3. In combination with a stringed musical instrument having a peg box, a frog seated on the peg box, screws extending through the frog and engaging the strings to apply a tension thereto adjacent the pegs, and a micrometer adjustment on said screws, the frog being stepped and the screws extending through the frog in said steps, and nuts threadingly engaged with the screws and bearing upon the steps of the frog, those ends of the screws remote from the nuts being formed with laterally opening slots in which the strings seat.

ERNEST WM. HOYT.
